UNITED STATES PATENT OFFICE

WILLIAM R. BANKSON, OF PITTSBURGH, PENNSYLVANIA

CONVEYER

Application filed June 29, 1929. Serial No. 374,722.

My invention relates to conveyers and while primarily intended for use as a mechanical toy, it will be obvious that the principle of the invention may be successfully embodied 5 in structural sizes adapted for industrial purposes.

Important objects of the invention are to provide a mechanical toy of the character described which embodies novel means for automatically transporting material from the 10 loading point and depositing the latter in an associated receptacle, which is simple in its construction and arrangement, durable and efficient in its use, entertaining, positive in 15 its action, attractive in appearance, and comparatively inexpensive to manufacture.

To the accomplishment of these and such other objects in view which will appear as the description proceeds, the invention resides in 20 the novel construction, combination and arrangement of parts herein specifically described and illustrated in the drawings, but it is to be understood that changes, variations and modifications may be resorted to that 25 come within the scope of the claims hereunto appended.

In the drawing wherein like numerals of reference designate corresponding parts throughout the several views:

30 Figure 1 is a side elevational view of the toy conveyer constructed in accordance with the invention, parts thereof being broken away and partly in cross section.

Figure 2 is a top plan view of the device.

35 Figure 3 is an end view of the carriage door.

Referring in detail to the drawing 1 denotes the frame of the structure, which may be constructed from any suitable material. The frame 1 comprises a base 2, a plurality of 40 spaced pairs of vertically disposed supports, respectively indicated at 3 and 4, and a pair of spaced horizontally disposed top members 5. The lower ends of the vertical supports 3 and 4 are fixed to the base 1 and the upper 45 ends thereof are fixedly secured to respective top members 5.

The forward ends of the top members 5 are fixedly joined by a cross piece 6 and project forwardly beyond the forward pair of vertical members 3 and 4. The rearward ends of

the top members 5 are also joined by a cross piece 7, and another cross piece 8 joins the rearward pair of vertical supports 3 and 4 adjacent to the upper ends of the latter.

A series of bell cranks 9, 10 and 11 are 55 mounted intermediate of the top members 5. Each of the bell cranks 9, 10 and 11 is fixed to a shaft 12 which has its ends suitably journaled for movement in respective top members 5.

Each of the bell cranks 9, 10 and 11 comprises a pair of arms, respectively indicated at 13 and 14. The bell crank arms 13 are uniform in length, while the bell crank arms 14 vary in length, for the purpose to be described.

A track member 15 extends longitudinally between the pairs of vertical supports 3 and 4 adjacent to the upper ends of the latter. The track member 15 is carried by the suspension rods 16, which are pivotally connected therewith and with the outer ends of the arms 14 of respective bell cranks 9, 10 and 11. The forward end of the track member 15 is pivotally connected to a suspension rod 17 which has its upper end fixed to the cross piece 6.

The outer ends of the arms 13, of the respective bell cranks 9, 10 and 11, are pivotally connected to an actuating bar 18. The forward end of the latter is pivotally connected to an upwardly disposed operating lever 19. The lower end of the operating lever 19 is pivotally connected to the top of the cross piece 6.

A carriage 20, provided with two pairs of aligned wheels 21, is suspended from the track member 15. The rearward end of the carriage 20 is open and is provided with a door 22, which is pivotally connected to respective top edge margins of the side walls of the carriage 20. The pivotal connection of the door 22 is such that the latter will normally swing to its perpendicular closing position by gravity.

The door 22 is maintained in its closed position by its engagement with a resilient latching element 23 which is fixed to and projects rearwardly from the rearwardly sloping bottom 24 of the carriage 20. The door

22 is formed with an upwardly disposed extension 25 which is adapted for engagement by the stop pins 26 and 27. The stop pins 26 and 27 are fixed to depend from the lower side of the track member 15 and are arranged in the path of travel of the carriage 20, for respectively unlatching and latching the door 22 during the travel of the latter on the track member 15.

10 The relative lengths of the arms 14, of the bell cranks 9, 10 and 11, is such that when the operating lever 19 is pushed rearwardly, the bell cranks 9, 10 and 11 will be actuated to incline the track member 15 downwardly toward its rearward end and the carriage 20 will travel by gravity on the track member 15, toward the rearward end of the latter. By drawing the operating lever 18 forwardly, the bell cranks 9, 10 and 11 will be actuated to elevate the rearward end of the track member 15, thereby causing the carriage 20 to travel toward the forward or loading end of the track member 15.

15 The rearward end of the track member 15 is disposed between the cross pieces 7 and 8, and the latter serve to limit the degree of inclination permitted, in respective directions, by the operation of the lever 19.

20 The operating lever 19 is provided with a toothed quadrant 28 and an associated catch mechanism 29, whereby the track member 15 may be adjusted and secured at any inclination permitted between the cross pieces 7 and 8.

25 An inclining channel chute 30, is fixed to dispose between the pairs of vertical supports 3 and 4. The upper rearward end of the chute 30 is positioned adjacent to the upper ends of the rearward pair of supports 3 and 4, while the lower forward end thereof is positioned adjacent to the lower ends of the forward pair of supports 3 and 4. A removable receptacle 31 is adapted to be positioned directly below the lower forward end 30 of the chute 30, on the base 2, to receive any material being deposited by the latter.

35 The device may be employed to convey sand, marbles, or any other suitable material and operates as follows:—Assuming that all parts of the device are in the positions shown in Figure 1, the operating lever 19 is first drawn forwardly to elevate the rearward end of the track member 15. The carriage 20 will travel forwardly by gravity to the loading position until the door extension 25 strikes the stop pin 27. The latter will cause the door 22 to engage the latch 23, and will further arrest or limit the forward movement of the carriage 20 on the track member 15.

40 The operator now deposits the material from the receptacle 31 into the carriage 20 and shifts the operating lever 19 rearwardly to the lower track member 15. The carriage 20 will now travel rearwardly with its load until 45 the door extension 25 strikes the stop pin 26.

The latter will release the door 22 from its latch 23 and cause same to shift to the open position, whereby the material will flow from the carriage 20 into the elevated end of the chute 30. The material will travel by gravity in the chute 30 and is again deposited in the receptacle 31. The rearward travel of the carriage is limited by the engagement of the door 22 with the stop pin 26 and with the cross piece 8.

75 It will be apparent that the device may be of any desired length to provide for the prolonged travel of the carriage 20 and material, and further that the track member 15 may be readily adjusted to inclinations controlling the speed of the carriage 20 on the track member 15.

80 The present invention provides a most efficient device of its kind, which is very interesting and entertaining, and which can be 85 constructed at a very low cost.

85 What I claim is:

1. In combination, a conveyer of the character described comprising a frame structure, a track member mounted in said frame structure and having the forward end thereof pivotally connected with the latter, a carriage suspended from said track member having a sloping bottom and provided with a door pivotally connected therewith, a shifting mechanism carried by said frame structure for shifting said track member to cause the travel of said carriage in either direction on the latter, an inclined channel chute mounted in said frame structure and having its upper end disposed adjacent to the rear end of said track member, a securing element carried by said carriage for securing said door in closed position, means fixed in the rear end of said track member and engaging said door for automatically releasing the latter from said securing element, and means fixed in the forward end of said track member and engaging said door for automatically moving said door to closed position.

90 100 105 110 115 120 125 130

2. In combination, a material conveyer of the character described comprising a frame structure, a track member mounted in said frame structure and having the forward end thereof pivotally connected with the latter, a carriage having a rearwardly sloping bottom and provided with a door pivotally connected therewith, a shifting mechanism carried by said frame structure for shifting said track member to cause the travel of said carriage in either direction on said track member, said mechanism being further operable for controlling the speed of the travel of said carriage on said track member and for maintaining the latter in position, an inclined channel chute mounted in said frame structure and having its upper end disposed adjacent to the rear end of said track member, a securing element carried by the bottom of said carriage for securing said door in

closed position, a stop pin fixed in and depending from the rear end of said track member and engaging said door for automatically releasing and opening the latter to allow the
5 passage of the material from said carriage to said channel chute, and a stop pin fixed in and depending from the forward end of said track member and engaging said door for automatically moving said door to closed position, said last mentioned stop pin further
10 limiting the forward movement of said carriage on said track member.

In testimony whereof I affix my signature.
WILLIAM R. BANKSON.
